GARMENT HANGER

John Thomas Pollard, East Providence, R. I.

Application January 3, 1939, Serial No. 249,098

1 Claim. (Cl. 223—93)

The present invention relates to garment hangers, and more particularly to the so-called coat hanger, and has for its primary object to provide means for securing the garment against accidental displacement on the hanger.

More specifically, the invention comprises a wire coat hanger in which the suspension hook is formed at the intermediate portion of the wire and after the wire is shaped to provide the oppositely extending shoulder supporting portion, the ends of the wire being formed with hooks and adapted to be positioned in overlying relation with respect to the garment when placed on the hanger to secure the garment against displacement thereon.

A further object is to provide a device of this character of simple and practical construction, which is efficient and reliable in performance, relatively inexpensive to manufacture and otherwise well adapted to the purposes for which the same is intended.

Other objects and advantages reside in the details of construction as more fully hereinafter described and claimed, reference being had to the accompanying drawing forming part hereof, wherein like numerals refer to like parts throughout, and in which—

Figure 1 is a perspective view showing the ends of the wire in position for securing the garment on the hanger.

Figure 2 is a perspective view of the hanger removed from the garment, and

Figure 3 is a similar view embodying a modified form of the invention.

Referring now to the drawing in detail, the numeral 5 designates the wire coat hanger generally which has its intermediate portion bent to form the suspension hook 6 which has its shank portion twisted as at 7 to reinforce the same, the portions of the wire extending oppositely from said hook to form the shoulder accommodating portions 8 of the hanger.

The extremities of the shoulder extensions 8 are formed with coils 9 which act as springs to

normally urge the end portions 10 of the hanger into a substantially horizontal position, as shown at Figure 2 of the drawing.

The extremities of the end portions 10 are formed with hooks 11 so that after the garment, indicated by the dotted lines 12, is placed in position on the hanger, the hooks 11 may be engaged over the top of the garment for bearing against the shoulder portions 8 to secure the garment against accidental removement from the hanger 10 in a manner as will be apparent.

In the modified form of the invention illustrated in Figure 3 of the drawing, the shoulder extensions 12 are formed with a return bend 13 at the outer portions thereof, to form the horizontal end portions 14, in this form of the invention the coils 9, as shown in Figures 1 and 2 of the drawing, being omitted.

It will also be understood the hanger may be constructed of two wire sections joined together at the twisted shank of the suspension hook end with their free ends shaped to form the hooks 11.

It is believed the details of construction and manner of use of the device will be readily understood from the foregoing without further detailed explanation.

Having thus described the invention, what I claim is—

A coat hanger formed from a single strand of wire and having its intermediate portion bent to form a suspension hook, the wire extending oppositely from said hook to provide shoulder accommodating portions, the ends of the wire extending inwardly from the outer ends of said shoulder portions in a direction toward each other and terminating adjacent an opposite side of the hanger to provide a pair of parallel horizontal bars, and hooks formed on the extremities of said ends and adapted upon a bending of the bars for engagement with an opposite shoulder portion for securing a garment in position thereon.

JOHN T. POLLARD.
